BAG

Russell J. Williams, Clayton, Mo., assignor to Bemis Bro. Bag Company, St. Louis, Mo., a corporation of Missouri

Application August 18, 1958, Serial No. 755,715

8 Claims. (Cl. 229—62.5)

This invention relates to bags, and more particularly to pasted valve bags such as are used for finely divided or pulverized materials (fertilizer, for example) and which are filled by means of a filling spout received in the valve.

Among the several objects of the invention may be noted the provision of a pasted valve bag of the class described having an improved valve construction including a novel sleeve which permits free flow of material from the filling spout into the bag so as to avoid clogging, and which provides for tight closure of the bag upon removal from the filling spout after the bag has been filled; the provision of a valve construction such as described in which the sleeve includes a special check valve member which is adapted to permit the stated freeflow of material into the bag during the filling of the bag and which closes when the bag has been filled; and the provision of a bag with a valve construction having the stated characteristics which is economical to manufacture. Other objects and features will be in part apparent and in part pointed out hereinafter.

The invention accordingly comprises the constructions hereinafter described, the scope of the invention being indicated in the following claims.

In the accompanying drawings, in which one of various possible embodiments of the invention is illustrated,

Fig. 1 is a perspective view of a pasted valve bag in which the invention is incorporated, the bag appearing as if filled;

Fig. 2 is a plan view of the valve corner portion of the bag, parts being shown in a condition assumed during the formation of the closure;

Fig. 3 is a perspective view of the valve corner portion of the bag with certain side flaps opened up better to show the construction; and

Fig. 4 is a perspective view of the valve sleeve per se as it appears when viewed from its bottom.

Corresponding reference characters indicate corresponding parts throughout the several views of the drawings.

Referring to the drawings, there is indicated at 1 in Figs. 1-3 a pasted multiwall paper bag provided with a valve of this invention. As will be understood by those skilled in the art, such bags are usually made by segmenting a continuous length of multiwall bag tubing into individual bag tubes, and providing each such tube with a pasted closure at each end, for example a diamond fold type of closure. Fig. 1 illustrates the closure 3 at the valve end of the bag. As appears in Figs. 1-3, the closure comprises side flaps 5 and 7 and inwardly directed end flaps 9 and 11. End flap 9 is the end flap at the valve corner of the bag. In forming the closure 3, the side flap 5 is folded over upon a transverse fold line 13 to overlie the end flaps, and the side flap 7 is folded over upon a transverse fold line 15 to overlap the side flap 5. A pattern of paste such as indicated at P is applied to accomplish pasting of side flap 5 to end flap 11 (the end flap opposite the valve corner) and pasting of side

2

flap 7 to side flap 5. Each side flap, as folded over, includes portions of the end flaps, such as portions 9a and 9b of end flap 9.

In accordance with this invention, a special valve sleeve S of this invention is applied to end flap 9 prior to the folding over of the side flaps and becomes incorporated in the closure 3, projecting inward from end flap 9 into the bag. Sleeve S is constituted by a rectangular piece of flexible material, such as kraft paper, folded on fold lines 17 and 19 (which extend lengthwise of the completed sleeve) into the form of a flattened tube. One wall of the flat tubular sleeve S is constituted by the portion of the piece of material lying between fold lines 17 and 19 and is designated 21. The other wall of the flat tubular sleeve S is constituted by the portion 23 of the piece of material lying between fold line 17 and edge 25 of the piece of material, and by the portion 27 of the piece of material lying between fold line 19 and the edge 29 of the piece of material. Portion 23 is wider than portion 27 and overlaps the latter on the outside thereof. The width of portion 27 is preferably half the total width of the sleeve so that the edge 29 is located centrally in respect to the width of the sleeve. The lapping side margins of the piece of material are specially designated 23a and 27a, 23a being a part of portion 23 and 27a being a part of portion 27, 23a being on the outside of 27a.

Margin 23a is provided with a slit 31 extending transversely from its edge 25. The length of the slit, as shown, corresponds generally to the width of the lapping margins 23a and 27a. Margins 23a and 27a are shown as being secured together by paste at 33 from the slit 31 to one end 35 of the sleeve, this end 35 of the sleeve constituting what may be termed its outer end in relation to the position of the sleeve on end flap 9. From the slit 31 to the other end 37 (the inner end) of the sleeve, margin 23a is free of margin 27a, and this free portion of the margin 23a constitutes a check valve flap designated F.

The sleeve S, made as above described, is applied to the outside of end flap 9 with the wall of the sleeve constituted by portions 23 and 27 facing toward the end flap 9, with slit 31 located slightly inward from the inner end edge 39 of the end flap 9, with the end 35 of the sleeve positioned on the flap 9 outward of the end edges of side flaps 5 and 7 and the portion of the sleeve from slit 31 to the end 37 of the sleeve projecting inward from the inner end edge 39 of end flap 9. The width of the sleeve corresponds to the width of the pasted closure as determined by the distance between the fold lines 13 and 15 of the closure. The sleeve is pasted to end flap 9 by paste P, and the pattern of paste P is such that side flap 5 (including portion 9a of flap 9) becomes pasted to wall 21 of the sleeve.

The sleeve S is adapted to receive a filling spout for filling the bag, spreading open upon insertion of a spout therein. The material delivered through the spout flows freely into the bag through the sleeve in the direction of the length of the sleeve and also in a lateral direction with respect to the length of the sleeve (downward into the bag), the flap F opening up away from margin 27a to provide an opening between edge 29 and the flap F for such lateral flow. When the bag has been filled and is taken off the spout, the sleeve flattens out and flap F is pressed against margin 27a by the bag contents to close off the opening and prevent escape of material.

It is preferable that the lapping margins 23a and 27a be pasted together at 33 in the region lying outward from the slit 31 in order to prevent the inner margin 27a from curling up away from the margin 23a and hanging up on the spout, but it is not essential that these margins be so pasted together, and the paste at 33 may in some instances be omitted.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. A bag having a closure at one end and provided with a valve at one corner at said end, said closure having an inwardly directed end flap at said valve corner and said valve comprising a flexible sleeve secured to and projecting inward from said end flap, said sleeve being constituted by a piece of flexible material folded into the form of a flattened tube in which one side margin of the piece of material overlaps the other side margin and lies on the outside of said other margin, said sleeve being adapted to receive a filling spout for filling the bag, and spreading open upon insertion of a spout therein, said lapping margins being located in one wall of said sleeve and said wall being secured to the outside of said end flap, said one margin having a slit extending transversely from the edge thereof, said slit being located between the inner end edge of said end flap and the inner end of sleeve, the portion of said one margin which extends from said slit into the bag constituting a check valve flap adapted to open up away from the other margin upon inserting a filling spout in the sleeve and upon delivery of material through the spout into the bag for permitting flow of material between the said margins, said check valve flap being adapted to close back over said other margin upon flattening out of the sleeve after withdrawal of the spout when the bag has been filled.

2. A bag as set forth in claim 1 in which the edge of said other margin is located centrally in respect to the width of the sleeve.

3. A bag as set forth in claim 1 in which the margins are secured together outward of the slit.

4. A bag as set forth in claim 1 in which the edge of said other margin is located centrally in respect to the width of the sleeve and in which the margins are pasted together outward of the slit.

5. A paper bag having a pasted closure at one end and provided with a valve at one corner at said end, said closure having an inwardly directed end flap at said valve corner, a first side flap overlying said end flap, and a second side flap overlying and pasted to said first side flap, said valve comprising a flexible sleeve pasted to and projecting inward from said end flap, said sleeve being constituted by a piece of flexible material folded into the form of a flattened tube in which one side margin of the piece of material overlaps the other side margin and lies on the outside of said other margin, said sleeve being adapted to receive a filling spout for filling the bag, and spreading open upon insertion of a spout therein, said lapping margins being located in one wall of said sleeve, the outer end portion of the sleeve lying between said end flap and said first side flap with said one wall of the sleeve pasted to the end flap and the other wall of the sleeve pasted to said first side flap, said one margin having a slit extending transversely from the edge thereof, said slit being located between the inner end edge of said end flap and the inner end of the sleeve, the portion of said one margin which extends from said slit into the bag constituting a check valve flap adapted to open up away from the other margin upon inserting a filling spout in the sleeve and upon delivery of material through the spout into the bag for permitting lateral flow of material between the said margins, said check valve flap being adapted to close back over said other margin upon flattening out of the sleeve after withdrawal of the spout when the bag has been filled.

6. A paper bag as set forth in claim 5 in which the edge of said other margin is located centrally in respect to the width of the sleeve.

7. A paper bag as set forth in claim 5 in which the margins are secured together outward of the slit.

8. A paper bag as set forth in claim 5 in which the edge of said other margin is located centrally in respect to the width of the sleeve and in which the margins are pasted together outward of the slit.
